AUTOMATIC VALVE AND SWITCH FOR FUEL BURNERS

Lucus T. Brockbank, Schenectady, N. Y.

Application October 4, 1954, Serial No. 459,966

2 Claims. (Cl. 158—42.4)

This invention relates to improvements in electrically controlled fuel burner furnaces, having particular reference to an automatic safety device to be connected between the burner and fuel supply, whereby simultaneously, as well as instantaneously, to shut off the flow of fuel and to stop the operation of the burner and its blower, and the provision of such a device is a principal object of the invention.

The invention is primarily directed to fuel burners utilizing liquid fuel, such as oil burners, wherein the oil is sprayed or atomized, and the disclosure of the invention is illustrated and described along these lines. However, it should be understood that it is also within the contemplation of the invention to apply the same to other types of electrically controlled burners, or furnaces, where it is desirable, in case of overheating and fire, similarly to shut off the fuel supply and stop the operation of the burners.

I am well aware that safety valves and other devices for shutting off the main supply of fuel, such as oil, leading to burners of furnaces, in case of fire, heretofore have been suggested, but these do not include means for preventing the flow or atomization of residual oil between the valve and burner in the manner disclosed and claimed hereinafter. Consequently, there may be an appreciable amount of such residual oil which may continue to be injected into the furnace after undue overheating and fire has already started, for example, in the stack, or, as the result of an explosion, puffing, or flare-back in the furnace, whereby the fire door is blown open. Continued heaping on or adding of fuel upon the flames for even a short length of time causes the fire rapidly to spread, usually and most quickly to the ceiling timbers, as well as elsewhere, with well known disastrous results.

It has long been recognized in the industry that it would be a distinct improvement if such difficulties and disadvantages could be overcome, and this now has been accomplished by means of the present invention.

Generally, it is another object of the invention also to provide such a device that is simple in construction, economic of manufacture and sale, positive in operation, will function with relative freedom from mechanical or other difficulties, and that otherwise is well suited to the purposes for which it is intended.

More specifically, it is an object of the invention to provide an automatically operable safety device for use in conjunction with an electrically controlled fuel burner furnace to be connected in the fuel line between the burner and fuel supply tank, constituting a shut-off valve normally held open when the burner is in operation, means connected to the valve normally to hold the same open, including a fusible element to be located in the vicinity of the furnace, or burner, where fire hazards are most likely to occur, an electrical shut-off switch, normally closed when the valve is open, and in circuit with the burner, and actuating means connecting the valve and switch, whereby simultaneously, as well as instant-

taneously, to close the valve and open the switch upon fusion of the element.

Other objects of the invention will in part be obvious and will in part appear hereinafter.

The invention accordingly comprises the features of construction, combination of elements, and arrangement of parts, which will be exemplified in the construction hereinafter set forth and the scope of the application of which will be indicated in the claims.

For a fuller understanding of the nature and objects of the invention reference should be had to the following detailed description taken in connection with the accompanying drawing, in which:

Fig. 1 is a schematic illustration of the invention connected between the burner of an oil type of furnace and an oil supply tank;

Fig. 2 is a side elevational view, with parts broken away, illustrating one embodiment of the invention;

Fig. 3 is a plan view substantially of Fig. 2;

Fig. 4 is a sectional view, with parts broken away, of Fig. 2; and

Fig. 5 is a side elevational view, with parts broken away, of a further embodiment of the invention.

Referring more particularly to the drawing, there is shown generally at 10 an automatically operable safety device for use in conjunction with an electrically controlled fuel oil burner 11 which is shown as a conventional burner including an electric motor driven blower mounted for use with a furnace 12 connected to the fuel line 13 between the burner and fuel supply tank 14. The device comprises a fuel shut-off valve 15 having a valve seat 16 adapted to receive a valve head 17 attached to the bottom of a valve-stem 18, slidably mounted in the top of the valve and extending therethrough. Between the head 17 and top of the valve 15, on the inside thereof, is a coil spring 19 encircling the stem which ordinarily urges the head 17 into the seat 16 when the device is not assembled, but which is normally held open against the action of the spring when the burner is being operated.

Preferably secured to the top of the valve is an arm 20 on which is pivotally mounted a lever 21 as at 22, the lever also being connected to the top of the valve-stem 18. At the free end of the lever 21 is a hook 22' preferably secured to a spring 23 which in turn is connected to a link, chain or cable 24. The cable at its opposite end should be secured to a brace 25 on the furnace smoke-pipe 26. The purpose of anchoring the other end of the link, chain or cable on the smoke-pipe adjacent the chimney is to operate the safety mechanism, or shut the burner off, in the event an explosion or puff should occur, which would loosen or disconnect the smoke pipe from its original position. The cable passes over one or more idler rollers 27 suitably positioned with respect to the furnace. At one or more suitable places in the cable are fusible elements, such as, for example, 28 above the fire door 29 and 30 above the smoke-pipe 26. It is at the fire door or smoke-pipe that overheating or fire usually occurs. The lever 21 is so fulcrumed against the valve-stem 18 by means of the cable 24 that it compresses the spring 19 in order normally to maintain the valve in an open position for the free flow of oil therethrough.

Secured to the valve in any suitable manner is a bracket 31 and attached to the bracket is a mechanical shut-off switch 32, conventionally known as a switchette having a plunger 33 which, when outwardly urged from within the switch by suitable means, permits the contacts therein normally to be closed. The switchette being conventional needs no further description. Also connected to the bracket 31 is a bell crank type of arm 34 being pivoted thereto at one end as at 35. At its opposite end the arm 34 has an adjustable screw 36 cooperatively associated with the plunger 33. Pivoted connecting the arm

34 and lever 21, as at 37 and 37', is an actuating link 38. Power wires 40 and 41 serve the burner 11 with its usual blower. Wire 41 is connected to one contact screw 39 of switch 32 and a wire 41' connected to the other contact screw 39 leads to a terminal box 50 on the burner 11. The other power wire 40 is shown connected directly to the terminal box 50. It will be seen, therefore, that upon tilting of cut off switch by lever 21 moving to the valve closed position the current through terminal box 50 will be cut off.

In operation, the valve 15 is normally opened to permit the free flow of oil therethrough and, the switch 32 being normally closed, the burner 11 continues intermittently to function in the well-known manner, such as, for example, by a conventional thermostat (not shown). However, should faulty operation of any kind occur in the system which would result in overheating, for example, in the smoke-pipe 26, or in the furnace itself, and an explosion, or puffing should occur, whereby the fire door 29 should be blown open, and a fire result, the fusible elements 28 and 30 would melt, thereby releasing the lever 21 so that the valve head 17 of the valve-stem 18 would locate itself in the valve seat 16, through the action of the spring 19, thus instantaneously shutting off the flow of oil. Since an appreciable amount of residual oil that has already passed through the valve 15 may remain in the line between the valve and burner 11, the same would continue to burn for some time if the burner were permitted to continue its operation. This is prevented, however, by the simultaneous opening of the switchette 32 since the actuating link 38 instantaneously depresses the bell crank type of lever 34 carrying the screw 36 which in turn actuates the plunger 33 so that immediately the burner stops functioning as the flow of oil is checked.

The principle of operation embodied in the modified form of switch shown in Fig. 5 is the same. In this view there is shown an outlet box 44 (with the cover removed) that is attached to the bracket 31. Secured within the box is a lever 34' pivoted at 45 carrying a conventional mercury switch 46 connected to lead-in wires 40' and 41'. At the other end of the arm 34' is an actuating link 47 pivotally connected to the lever 21 as at 48 and 49. The operation of the device, whether using a conventional mercury switch or a conventional switchette, is the same.

It will thus be seen that the objects hereinbefore set forth may readily and efficiently be attained, and since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims

are intended to cover all of the generic and specific features of the invention herein described, and all statements of the scope of the invention which, as a matter of language, might be said to fall therebetween.

Having described my invention what I claim as new and desire to secure by Letters Patent is:

1. In the combination of an oil burning furnace and a safety device, said furnace being of the type having a fire box, a fire box door, an electrically controlled burner including an electrically operated blower, a remotely located source of fuel, a fuel line connecting said fuel source and said burner, an electric control circuit for said blower, and a smoke-pipe connecting said fire box to a chimney; a safety device comprising a fuel shut off valve in said fuel line adjacent said burner and having a valve head mounted on a valve stem extending out of said valve, a spring in said valve biasing said valve to cut off position, a bracket mounted on the exterior of said valve, an electric switch of the type operated by tilting pivotally mounted on said bracket and interposed in said electric circuit, lever means pivoted to said valve and secured to said valve stem whereby said valve may be held in open position against said spring, link means connecting said pivotally mounted switch to said lever so that said lever and switch will pivot simultaneously, said switch being so positioned with relation to said lever that said switch is closed when said lever is in a position holding said valve open, cable means having one end secured to said lever to hold said lever in a position in which said valve is held open and said switch is held closed, means to secure the other end of said cable means to said smoke-pipe and at least one fusible link means interposed in said cable means at the connection of said cable means to said smoke-pipe whereby upon disconnection of the smoke-pipe by explosion or fusion of the fusible link by over-heating the fuel will be cut off and the electric circuit to the blower will be interrupted.

2. The device of claim 1 in which a second fusible link is provided which is interposed in said cable means adjacent said fire door of said furnace whereby upon fusion of said link by heat from said fire door said switch and said valve will be activated to cutoff positions.
